UNITED STATES PATENT OFFICE.

GEORGE H. DICKSON, OF CHICAGO, ILLINOIS, ASSIGNOR TO THE BABCOCK & WILCOX COMPANY, OF BAYONNE, NEW JERSEY, A CORPORATION OF NEW JERSEY.

BOILER BAFFLE.

Application filed June 4, 1918. Serial No. 238,097.

My invention relates to the construction of baffles used in boilers, and will be understood by reference to the accompanying drawings in which Figure 1 is a side view of a portion of two banks of tubes of a water tube boiler with the baffle in section and with spacing strips in place before pouring the plastic material; Fig. 2 a view similar to Fig. 1 with the spacing strips removed and the baffle ready for pouring; Fig. 3 a similar view of the baffle as completed after pouring; and Fig. 4 a vertical section on the plane of the line 4—4 of Fig. 1. Similar reference numerals indicate similar parts in the several views.

Referring to the drawings the numeral 1 designates a portion of the tubes of a water tube boiler the tubes being arranged in two groups or banks. It has been customary to build the baffles, of this type of boiler, of walls of tiling and cast iron flame plates resting upon the tubes. I have retained this general character of baffling but have separated the walls of tiling and interposed between them a wall of poured plastic material and also, where desired or necessary, a wall of plastic material between the flame plate and one of the walls of tiling. The tubes are shown as divided into two banks with an interposed wall of fire brick 2 resting upon the upper row of tubes of the lower bank. The lower part of the baffle, as shown, rises from the bridge wall 3. In the practice of my invention I proceed as follows:

I build up the two walls 4 and 5 of the usual tile blocks fitted around and supported upon the boiler tubes, with spacing strips 6 between them and with the tiling braced by wood cross pieces 7 held in place by blocks 8 forced between them and the tubes. The baffle also comprises a flame plate 9 made up, as usual, of inner and outer cast iron plates with asbestos plates between them, spacing strips 6 being placed between the lower flame plate and the inner lower wall 5. A permanent retaining cross piece 10 comes between the upper and lower sections of the flame plates and holds the ends of the pieces which make up the flame plates, in alignment. The upper flame plate is held at its upper end by corrugated backing bars 12 which bars are in turn held by tube clamps 13. The lower flame plate 9 is held at its lower end by the Z-bar 11 and by corrugated bars 12' the ends of which are embedded in the furnace walls. In the arrangement shown, the upper flame plate 9 is placed against the inner wall of tiling 5, while the lower flame plate is spaced apart from the lower wall of tiling 5. The upper walls of tiling 4 and 5 are spaced further apart than are the corresponding lower walls.

With the parts arranged and built up as shown in Fig. 1, I then remove the spacing strips 6, as shown in Fig. 2, and pour the form so prepared with any suitable grouting to fill the space between the walls 4 and 5, and that between the lower wall 5 and the lower flame plate 9, as indicated in Fig. 3. When the grouting is set, the braces 7 and 8 are removed.

For the grouting I have used a mixture of finely ground fire brick, asbestos fibre, Portland cement and fire clay. The particular grouting used, however, may be varied to suit particular conditions and the proportions of the ingredients may be changed as desired. For the initial pouring the grouting should be of relatively thin consistency so that it may find its way to the bottom of the spaces between the lower walls of tiling and the flame plate. The use of asbestos in the mixture is of advantage in that the fibre closes the cracks and assists in preventing an undue amount of leakage of the plastic material when being poured.

Various modifications may be made in the baffle as described, as, for example, the present method may be employed for constructing a baffle one side only of which is faced with refractory tiling; for example in Figure 1, the line of tiling 5 may be omitted, and the entire space between the line of tiling 4 and the flame plates 9, filled in with poured plastic material. Again, if desired, the flame plates 9 may be removed after the plastic material has set, and the resulting baffle will then consist of a baffle, one side of which is faced with refractory tiling, and the body of which is of material, which, before it is placed in position and becomes set and hardened, is in a plastic state.

What I claim and desire to secure by Letters Patent of the United States is:

1. A baffle for water tube boilers consisting of two separated walls extending across and surrounding the tubes, each of said walls comprising a plurality of tiles at least

partly in contact with and resting on the water tubes to form a substantially closed side of a mold, each tile being less in width and height than the width and height of the baffle and a layer of poured and hardened plastic material between and held by said side walls.

2. A baffle for water tube boilers consisting of two separated walls extending across and surrounding the tubes, each of said walls comprising a plurality of tiles at least partly in contact with and resting on the water tubes to form a substantially closed side of a mold, each tile being less in width and height than the width and height of the baffle, a layer of poured and hardened plastic material between and held by said side walls, and a separate tile between each pair of tubes in each horizontal row.

3. A baffle for water tube boilers consisting of two separated walls extending across and surrounding the tubes, each of said walls comprising a plurality of tiles at least partly in contact with and resting on the water tubes to form a substantially closed side of a mold, each tile being less in width and height than the width and height of the baffle, and a layer of hardened plastic mate-

rial between and held by said side walls, said plastic material containing fibrous matter.

4. A baffle for water tube boilers consisting of two separated walls extending across and surrounding the tubes, each of said walls comprising a plurality of tiles at least partly in contact with and resting on the water tubes to form a substantially closed side of a mold, each tile being less in width and height than the width and height of the baffle, a layer of hardened plastic material between and held by said side walls, and a separate tile between each pair of tubes in each horizontal row, said plastic material containing fibrous matter.

5. A baffle for water tube boilers comprising two separated walls extending across and surrounding the tubes, at least one of said walls comprising a plurality of tiles at least partly in contact with the water tubes to form the closed side of a mold, each of said tiles being less in width and height than the width and height of the baffle, and a layer of poured and hardened plastic material between and held by said walls.

In testimony whereof I have hereunto signed my name.

GEORGE H. DICKSON.
